UNITED STATES PATENT OFFICE.

FRANK HOWARD POCHIN AND HORACE STANLEY POCHIN, OF LEICESTER, ENGLAND.

APPARATUS FOR USE IN ATTACHING SOLES TO THE LASTED UPPERS OF BOOTS AND SHOES.

Application filed June 7, 1927, Serial No. 197,038, and in Great Britain June 8, 1928.

This invention has reference to improvements in or relating to apparatus for use in attaching soles to the lasted uppers of boots and shoes.

5 A method of attaching soles to the lasted uppers of boots and shoes which has comparatively recently come into use—although the method per se has long been known—is to roughen the marginal portion of the lasted 10 upper and the insole and to apply an adhesive on the roughened surfaces, allowing the adhesive (which usually is a celluloid cement) to dry. The surface of the sole is similarly treated. When the parts are to be secured 15 together the roughened and coated surfaces are moistened with a solvent of the adhesive and usually more adhesive is applied to said surfaces and then the sole is applied in correct position on the lasted shoe and the two 20 are pressed together and held until the adhesive has set.

25 This method of procedure lends itself admirably to the repairing of boots and shoes (both hereinafter included in the term shoes) and an object of our invention is the provision of a very simple apparatus for the use more especially of shoe repairers and which is adapted to deal with all kinds of work whether for applying a half or a full 30 sole.

35 Our invention is illustrated diagrammatically in the accompanying drawing in which Fig. 1 shows the apparatus in side elevation; Fig. 2 is a sectional view showing the main part adapted for half-sole work; Fig. 3 is a similar view adapted for whole-sole work; and Fig. 4 is a sectional view of a detail.

40 The numeral 3 indicates an iron container that is to be more or less filled with water and has applied to it a sheet of rubber 4 and on this a leather or strong canvas outer and protecting cover 5, these two being tightly secured on the rim of the container at the front and sides by a metal frame 6 and bolts or screws such as 7, and at the end by being carried down the back 11 of the container and tightly pressed against it by a plate 8 that is secured by studs such as 9 having a 45 projecting cylindrical head 10 and outside this a hexagonal head 13 that is suitable for engagement by a spanner. At the part 12 the container is made to project upwardly and at this part plate 8 is formed suitably so that the marginal portions of the sheets

4 and 5 are held in tight engagement against 55 the rim of the container by studs such as 14, having preferably cheese heads. The container is provided with a jet 30 and valve 31 and with a filling funnel 32 and valve 33.

5 A Adapted to be engaged between the plate 8 60 and the heads 13 of the studs 9 and also adapted to be engaged on the cheese-heads 14, is provided a sort of cup 16 to receive a rubber block 18 having a gradually tapering tongue 19 projecting forwardly from its upper front 65 edge. Lying on the block 18 and on the tongue 19 is a leather flap 20 the front end of which is skived so that the flap has its front part of gradually diminishing thickness and the rear end of the flap is turned 70 over the back of the cup and secured to it by one or more screws 22 and washers 23.

75 There is also provided a pressure plate 25, the front end of which has a depending part 26 on which a pad 27 is secured. The pad 75 may be attached hingedly as at 28.

80 At each side of the container 3 is a boss 36 to which bosses a frame 37 is hingedly connected by screw bolts, as 35. The frame 37 carries a nut 38 to receive a screw 39 that is provided with a hand-wheel 40 so that by 85 rotating the wheel the screw will press on the pressure plate 25 and through it the fore-part of the shoe 41 will be pressed down on the leather protected yielding cover 4, 5, and 85 the heel part, when a whole-sole is being applied, on the yielding pad or block 18. For convenience of packing for transport, the bolts 35 may be slackened back and the frame 37 laid down level with the container 3. If 90 desired, however, the frame 37 may be secured to the container in a different manner, for example by its vertical side members screwing into lugs or sockets projecting from the sides of the container 3. The upper face of 95 the pressure plate 25 will preferably be provided with a series of cavities 44 in one or other of which the lower end of the screw 39 is engaged.

100 In using the apparatus, and supposing a half-sole is to be applied to a shoe, the workman, having removed the worn sole, will clean the surface of the sole portion and will roughen it and apply a suitable adhesive thereto. A viscous solution in the nature of 105 celluloid is, we find, very suitable. The adhesive is then allowed to dry. The half-sole, already cut to approximately the finished

shape is similarly treated, that is to say its inner or shoe contacting surface is roughened and the adhesive then applied and allowed to become dry.

5 The drying of the adhesive has the effect that the celluloid solution creeps into the fine interstices of the rough surface of the material and firmly clings to the fine shreds or fibres produced during the roughing process.

After this, the shoe and the sole are moistened with the solvent of celluloid or other adhesive employed and a further thin coating of the adhesive is applied. The shoe, on a last 15 and with the half-sole placed in proper position thereon at the fore-part, is next placed on the leather protected yielding cover 4, 5, of the water filled container 3; the pressure plate 25 is next placed thereon, the pad 27 20 engaging on the fore-part of the shoe and the rear portion of said plate—which has a short depending part 29—engaging on the last of the shoe, and then the hand-wheel 40 is rotated to cause the pressure plate to press the 25 shoe firmly down on the yielding surface 4, 5.

If the newly applied half-sole is thin, it is desirable that its marginal portion should be more or less bent upwardly so as to ensure that this part comes into contact with the 30 slightly rounded marginal portion of the upper at its junction with the insole and to attain this it is necessary that the sole and shoe should sink into the yielding leather protected cover 4, 5 or surface on which the sole rests 35 whereby the yielding cover wraps itself upon the sole and thereby presses it firmly into engagement with the lasted upper at every position and particularly around the edges. For this purpose the workman will open the valve 40 31 so as to let some of the water within the container 3 escape and he will let more or less of the water escape according to the character as aforesaid of the half-sole and of the shoe to which it is being applied. For a thick and 45 almost unyielding sole he may find it desirable to maintain the container completely or nearly filled.

The workman then applies the final pressure by rotating the hand-wheel 40 and will 50 allow the shoe to remain under pressure until the adhesive has set.

The fellow shoe, being presumably of a similar character, may be applied in position and the final pressure at once applied without 55 requiring the workman to effect adjustment by allowing water to escape as already described.

If a number of pairs of shoes of the same character are to be dealt with, the adjustment 60 of the water content of the container effected to suit the first shoe will suffice for all the shoes.

If a thick half-sole is to be applied to a shoe after shoes having thinner half-soles applied, 65 the workman simply turns the apparatus on

end and opens the valves 33, 31 and pours water through the funnel 32 into the container, the air displaced escaping from the jet 30. He then closes the valves and replaces the apparatus to its normal position and proceeds as already described.

If a full sole is to be applied—in which case not only the worn sole but the heel also will be removed—the workman hooks or engages the cup-like member 16 on to the stud 14 and 70 the stud or cylindrical head 10, the head (or heads) 13 serving to maintain said cup in position. He then carefully adjusts the tapering tongue 19 on the pad 4, 5, and also carefully adjusts the leather covering flap 20, to 80 ensure that the front ends of the tongue 19 and flap 20 form a gradually diminishing support that is to be engaged by the waist of the shoe—as shown in Fig. 3. He then proceeds in the manner already described with 85 reference to the half-sole.

In either case he will adjust the pressure plate 25 according to the shape and size of the shoe about to be operated on.

It is to be observed that the cupped bracket 90 16 is provided with a downwardly projecting flange 15 to fit against the plate 8 on the rear end of the container 3, and with an upwardly and forwardly extending flange 17 to fit against the inclined face of the upwardly extending part 12 of said plate, the flange 17 being slotted to receive the head 14 of the stud whereby the plate 12 is secured so as to pinch the marginal portion of the flexible cover 4, 5, against the rim of the container so that 100 when the apparatus is required to be employed for repairing shoes by attaching whole soles, it is only necessary to "drop" the cupped bracket into position, or, when half-soles are 105 to be attached, to lift up and remove said bracket. There is thus no loss of time in converting the apparatus from one use to the other.

The apparatus is preferably made in duplicate so that the operator after having dealt 110 with one shoe of a pair may at once proceed to deal with the fellow shoe.

It will be observed that the tapering tongue 19 and the tapering flap 20 thereon ensure a firm support to the sole at the waist of the shoe when pressure is applied, the yielding cushion 4, 5 adapting itself to these tapering parts and exerting pressure upon the sole therethrough.

An important practical advantage derivable from the use of our improved apparatus for repairing shoes by applying a full sole, is that the forepart and waist of the shoe, where the sole and shoe are of irregular curvilinear shape, are acted upon by an hydraulic pad 120 that instantly adapts itself to every part of the forepart and waist whatever be their shape when pressure is applied as stated, whereas at the heel end the relatively rigid block that is provided to resist the pressure of 125 130

the shoe and sole at that part will practically ensure the production of a level surface for the reception of the heel.

It will be understood that although our improved apparatus is principally intended for use by repairers of shoes, it is also adapted for use in making new shoes.

Claims:—

1. Apparatus for use in attaching soles to boots and shoes comprising a fluid container, a flexible fluid-tight closure for the said container through which closure fluid pressure may be applied upon the under surface and around the edge of the forepart of a sole, and
2. a substantially rigid part having a resilient surface through which pressure may be applied upon the waist and heel portion of the sole.

2. Apparatus for use in attaching soles to the lasted uppers of boots and shoes, comprising a fluid container, a flexible fluid-tight closure for the said container, upon which closure the lasted upper with the sole in position for attachment is disposed, a cup-like part extending rearwardly from and rigidly secured to the said container, a block of resilient material supported upon the said cup-like part, the said block being of a shape conforming substantially to the under surface of the rear part of the sole in position upon the lasted upper and having at the front a tapering part which extends above and overlaps the rear part of the said flexible closure, and means for exerting fluid pressure upon the sole through the said flexible closure whereby the latter wraps itself upon the sole and thus presses firmly and evenly upon the under surface and around the edge of the sole.

3. Apparatus for use in attaching soles to the lasted uppers of boots and shoes, comprising a fluid container, a flexible fluid-tight closure for the said container, upon which closure the lasted upper with the sole in position for attachment is disposed, a cup-like part extending rearwardly from and rigidly secured to the said container a block of resilient material supported upon the said cup-like part, the said block being of a shape conforming substantially to the under surface of the rear part of the sole in position upon the lasted upper and having at the front a tapering part which extends above the rear part of the said flexible closure, a protecting cover of leather secured to the rear part of the said cup-like part and extending over the said block of resilient material, and means for exerting fluid pressure upon the sole through the said flexible closure whereby the latter wraps itself upon the sole and thus presses firmly and evenly upon the under surface and around the edge of the sole.

4. Apparatus for use in attaching soles to

the lasted uppers of boots and shoes, comprising a fluid container, a flexible fluid-tight closure for the said container upon which closure the lasted upper with the sole in position for attachment is disposed, a detachable cup-like part having a depending flange to engage the end wall of the container, said flange having open-ended slots, headed studs extending from said container and received in said slots, a block of resilient material supported by said cup-like part, the said block being of a shape conforming substantially to the under surface of the rear part of the sole, and means to press the sole against said flexible closure and said block.

5. Apparatus for use in attaching soles to the lasted uppers of boots and shoes, comprising a fluid container having a vertical end face and two side faces inclined upwardly and forwardly from the end face, a flexible fluid-tight closure for said container upon which closure the lasted upper with the sole in position for attachment is disposed, headed studs extending from said end face of the container and a projection extending from the upwardly-inclined face, a detachable cup-like part having a depending flange to fit said end face, which flange is provided with open-ended slots to receive the headed studs, said cup-like part having a forwardly-extending flange to fit against the forwardly- and upwardly-inclined face of the container, said flange being slotted to receive said projection, and a resilient pad in said cup-like part conforming to the shape of the under surface of the rear portion of the sole of the shoe.

6. Apparatus for use in attaching soles to the lasted uppers of boots and shoes, comprising a fluid container having a vertical end face and two side faces inclined upwardly and forwardly from the end face, a flexible fluid-tight closure for said container upon which closure the lasted upper with the sole in position for attachment is disposed, headed studs extending from said end face of the container and a projection extending from the upwardly-inclined face, a detachable cup-like part having a depending flange to fit said end face, which flange is provided with open-ended slots to receive the headed studs, said cup-like part having a forwardly-extending flange to fit against the forwardly- and upwardly-inclined face of the container, said flange being slotted to receive said projection, and a resilient pad in said cup-like part conforming to the shape of the under surface of the rear portion of the sole of the shoe, said pad having a forwardly-projecting lip to overlie the rear portion of the flexible closure.
